VALVE

Scott E. Allen, Glen Ridge, N. J., assignor to
C-O-Two Fire Equipment Company, Newark,
N. J., a corporation of Delaware

Application March 4, 1935, Serial No. 9,146

17 Claims. (Cl. 169—11)

The present invention relates to discharge mechanism for containers holding fluid under pressure, such, for example, as liquefied carbon dioxide, and the invention has for an object to provide novel means operable either manually or by fluid pressure or by manual means in combination with fluid pressure, to release the fluid from the container.

The discharge ports of containers holding fluid under pressure are usually closed by a sealing disk which must be ruptured or cut open to release the fluid. When the disk is cut by a manual operation it sometimes happens that the operation is arrested before the disk has been fully cut and my invention provides means whereby a partial opening in the disk will be automatically completed by means operated by the fluid released through said partial opening. The present invention is, therefore, a modification of that disclosed in copending application Serial No. 349,150, filed March 22, 1929, and differs therefrom in being applicable to a container having a lateral outlet instead of the usual vertical outlet closed by the sealing disk.

As in the discharge head described in said copending application the present discharge head is also operable by fluid pressure from an outside source. For instance, a battery of fluid containers may be connected to a single delivery line and the discharge of fluid into said line from any one of the containers will cause discharge of fluid from the rest of the containers. My invention provides further for preventing escape of fluid through a discharge head when it is uncoupled from a cylinder. Thus, at any time, any cylinder of a battery may be disconnected for test purposes without interfering with effective operation of the rest of the battery.

A further object of the invention is to provide a novel form of cutter for cutting a flap out of the sealing disk.

Other objects and advantages of my invention will appear in the following description of a preferred embodiment thereof and a modification 45 of the same and thereafter the novelty and scope of the invention will be pointed out in the claims.

In the accompanying drawing;

Figure 1 is a view in vertical section of my improved discharge head;

Fig. 2 is a similar view of another form of my invention;

Fig. 3 is a fragmental view of a portion of Fig. 2 showing the cutter in actuated position; and

Fig. 4 is a view of the sealing disk and cutter 55 at the end of the cutting stroke and at the instant

before the flap is bent into the cutter by the pressure of the discharging fluid, the disk being viewed in the direction of the arrow 4 in Fig. 3.

In Fig. 1 a cylinder for liquefied carbon dioxide or other highly compressed fluid is shown fragmentally at 10. An outlet fitting 11 is threaded into the neck of the cylinder and carries a siphon tube 12 extending into the cylinder in the usual manner. The fitting 11 has a central bore 13 which at its upper end is enlarged to form a seat 10 for a screw plug 14 which carries a gasket 15 so as to insure a gas tight seal of said bore. The plug 14 is formed with an upwardly extending shank 16 terminating in a squared end 17 which projects from the top of the fitting 11. To insure 15 against any possible leakage of fluid a suitable packing 18 is provided about the shank 16. A cap 19 is screwed over the end of the fitting 11 to cover the projecting squared end 17 of the shank and a gasket 20 is provided between the cap 20 and the casing.

As a means of filling the cylinder a suitable filling port 22 is provided in one side of fitting 11 above the seat for the plug 14. This port is normally closed by cap 23 and gasket 24.

Extending laterally from the central bore 13 below the plug is a safety port 25 which is normally closed by a safety disk 26 held in place by a ported screw plug 27. The safety disk is arranged to rupture at a predetermined pressure 30 so as to prevent the building up of excessive pressures in cylinder 10.

Another lateral port 30 below the plug 14 is normally closed by a sealing disk 31 which is clamped against a seat formed by an enlargement 32 of the port 30. The disk 31 has a higher rupture point than that of disk 26. A sleeve or tubular screw plug 33 is threaded into the enlargement 32 and clamps the disk 31 against its seat. The enlargement 32 extends through a 40 lateral projection 34 of the fitting 11. A cutter casing 36 is removably secured to this projecting portion 34 by a coupling nut 37 having right and left hand threaded engagement with said casing and projecting portion.

The casing 36 which extends substantially perpendicularly to the longitudinal axis of the fitting 11, has an axial bore formed with an enlargement to provide a discharge chamber 38. At the outer end of the casing 36 the bore is 50 further enlarged to form a working chamber 40 for a piston 41. This piston is fixed upon the solid shank 42 of a tubular cutter 43. This cutter at its inner end, that is the end toward the sealing disk 31 is stepped to provide a cutting edge 55

44 and a recessed part 45, each extending through an angle of about 180 degrees. This cutting edge coincides with the inner periphery of the tubular cutter 43. A set of ports 46 provides communication between the bore of cutter 43 and the chamber 38.

Leading outwardly from the chamber 38 is a discharge port 47 which, however, is constricted at its point of communication with the chamber 38 to provide a seat for a ball check valve 48. A ported disk 50 serves to limit outward movement of the ball 48. This ball normally occupies the closed position shown in Fig. 1 due to its weight. Obviously, however, if the port 47 were not upwardly directed from the chamber 38 a spring could be introduced between the member 50 and the ball 48 to hold the latter normally in closed position. The discharge port is usually connected to a delivery line 51, and cylinder 10 may be but one of a battery of cylinders similarly connected to the same line.

A duct 52 is formed in the casing 36, leading from the port 47 just below the member 50 to the working chamber 40 at the outer side of the piston 41. This working chamber is closed at its outer end by a head 54 which is formed with a tubular extension 55 through which passes a spindle 56. This spindle is formed with threads 57 which engage with corresponding threads in the head 54 and extension 55. The inner end of the spindle is provided with a socket 58 of squared cross-section which is adapted to receive the squared end 60 of the cutter shank 42. Fixed upon the outer end of spindle 56 is handle 61. The shank 42 has a shoulder 62 which bears against the end of the spindle 56. A suitable packing 64 separates chamber 38 from chamber 40 and a spring 65 normally holds the parts in the position shown in Fig. 1 with the shoulder 62 bearing against the end of the spindle 56. A vent 66 is provided at the inner end of the working chamber 40.

In operation, when it is desired to release fluid from the cylinder 10 the handle 61 is rotated in such direction as to feed the spindle 56 inwardly or toward the left, as shown in Fig. 1. This results in advancing the cutter 44 with a helical motion. The cutting edge 44 cuts through the sealing disk 31, cutting out a flap therefrom which is not a complete circle because before or by the time the blunt shoulder 45 engages the disk, the advance of the cutter will be checked by engagement of the piston 41 with the inner end wall of the working chamber 40. On the uncut portion integrally connecting the flap to the main body of the disk 31 the flap will hinge as it is forced out by the fluid in the cylinder 10 and pressed back against the inner periphery of the cutter 43. The fluid then escapes through the tubular cutter and out of the ports 46 into the discharge chamber 38 and thence past the check valve 48 into the delivery line 51. If, for any reason, the handle 61 is not operated sufficiently to make a complete cut of the disk 31 but causes the cutter to merely penetrate the disk slightly, the escaping fluid will act to complete the cutting operation, for the reason that part of the fluid will pass through the duct 52 to the outer side of the piston 41 and will depress said piston to the limit of its stroke, thereby forcing the cutting edge 44 completely through the disk 31. My invention, therefore, provides a self-energizing discharge head in which the discharging fluid supplements the manual operation, assisting the manual op-

eration or completing the opening where the manual operation is arrested prematurely.

The cutting edge 44 extends through an angle of at least 180 degrees and the cutter being initially turned by the manual operation of handle 61 and then forced bodily forward by the fluid pressure, will produce a cut of more than 180 degrees. The pressure of the fluid escaping from the cylinder 10 will tear the uncut part as the flap is being hinged outwardly but the parts are so proportioned that a hinge of sufficient width will always be provided to prevent the flap from being completely detached from the body of the disk 31. It is essential to make a cut with a minimum extent of substantially 180 degrees because the metal from which sealing disks is made is usually rolled and has a definite grain in the direction of rolling. The metal under pressure tends to split in the direction of this grain and if a cut of less than 180 degrees were made and this cut extended across the grain it would be apt to split off a piece of the disk and carry it forward into the tubular cutter where it would be likely to jam the openings 46. Such splitting might also result in an incomplete opening of the sealing disk.

It will be evident that the cutter can be operated by admission of fluid under pressure through the port 47 without operation of the handle 61. For instance, any cylinder connected to the delivery line 51 if discharged will build up sufficient pressure in the delivery line to force the piston 41 inwardly, particularly since the working chamber at the inner side of the piston is ported.

The particular object of the check valve 48 is to permit of uncoupling the cylinder from a battery of cylinders by unscrewing the nut 37 without in any way crippling the operation of the rest of the cylinders. If, for instance, when the cylinder 10 was disconnected, a fire should occur, the other cylinder could be discharged into the delivery line and the only result of admission of fluid pressure to the port 47 would be to depress the piston 41. There could be no escape of the fluid because of the valve 48 which prevents inflow toward the open end of the cutter 43.

The structures shown in Figs. 2, 3 and 4 differs from that shown in Fig. 1 particularly in the form of the cutter and in the location of the check valve, consequently parts which are substantially identical with those in Fig. 1 are given the same reference numerals, and corresponding parts that differ somewhat from those in Fig. 1, are designated by corresponding reference numerals bearing the suffix *a*.

The cutter casing 36a is secured to the fitting 11 by means of the coupling nut 37. This cutter casing 36a differs from the casing 36 in having a discharge port 47a in constantly open communication with the discharge chamber 38, and in having no duct formed therein to connect the port 47 with the outer end of the working chamber 40.

The cutter 43a differs from the cutter 43 in a number of particulars. In the hollow portion of the cutter there is an annular depression 70 which provides a seat for a ball check valve 71, the latter being normally pressed against its seat by a light spring 72. A duct 73 is formed in the solid shank 42a and provides communication between the tubular portion of the cutter and the working chamber 40 at the outer end of the piston 41. The bore 73 has slots 74 milled therein and the ball check 71 is of smaller diameter than that of the tubular part of the cutter 43a, so that when the ball 71 is forced back by fluid from the cylin- 75

der 10 (as shown in Fig. 3) it cannot completely cut off communication with the duct 73.

The cutter 43a also differs from the cutter 43 in the fact that it is not rotated when forced into engagement with the disk 31 by operation of the handle 61. The spindle 56a has a cylindrical socket 58a and receives a cylindrical pin 60a formed at the end of the shank 42a so that the spindle may be turned without rotating the cutter 10 43a. The spring 65 presses the end of the part 60a against a shoulder 75 formed in the bottom of the socket 58a. This spaces the inner end of the spindle from the outlet end of port 73 so that at no time is said port closed.

15 The cutting end of the cutter 43a instead of being stepped, has an endless arcuate cutting edge which is disposed in a plane inclined from normal to the longitudinal axis of the cutter. This cutting edge is formed by cutting the end 20 of the tubular cutter at a slant and then sharpening the end of the cutter toward the inner periphery of the cutter.

In operation, when the cutter is fed inwardly by operating the handle 61, said cutter may rotate, initially, due to frictional engagement with the spindle 56a, but once it has engaged the sealing disk 31 it will be held by such engagement against rotation and will then be advanced without rotation. The parts are preferably so arranged that penetration of the disk 31 will be arrested by engagement of the piston 41 with the bottom wall of the working chamber 40 when a cut has been made in the disk of more than 180 degrees but less than 270 degrees. Fig. 4 35 shows the position of the cutter and disk at the instant of extreme penetration of the cutter and just before the flap 76 has been bent outwardly by pressure of fluid from the cylinder 10. As this flap is forced outwardly it tears along the 40 lines 77 but it will not be torn off because before this can happen it will be folded back into the cutter in the position shown in Fig. 4 and further tearing will be arrested.

It will be observed in this construction, as in 45 that depicted in Fig. 1, that there is a self-energizing action which tends to assist or complete the manual cutting operation since fluid escaping from the punctured disk 31 will force back the check valve 71 and a certain part of it will enter the duct 73 by way of the slots 74 50 making its way to the outer end of the piston 41 and exerting sufficient pressure to completely depress said piston. Whenever fluid under pressure is admitted from some other cylinder through the port 47a into the chamber 38 it 55 enters the cutter 43a through the ports 46 on the outer side of the ball check valve 71 and then flows through duct 73 into the working chamber to effect operation of the cutter. Should the 60 coupling 37 be unscrewed and the cylinder 10 be removed for test, refilling or any other purpose, the rest of the battery of cylinders connected to the delivery line 51 may be discharged into the line without any danger of loss of fluid through 65 the uncoupled parts because the check valve 71 prevents flow from port 47a to the cutting end of the cutter 43a. The only result of such admission of fluid under pressure to the discharge chamber 38 will be to cause the piston 41 to 70 move toward the left, as viewed in Fig. 2, until the piston seats against the bottom wall of the working chamber 40.

While I have described a preferred embodiment of my invention and a modification thereof 75 it will be understood that my invention is not

limited to the particular constructions illustrated and that I reserve the right to make various changes in form, construction and arrangement of parts which fall within the spirit and scope of the following claims.

5

I claim:

1. A releasing device for a container holding fluid under pressure and having an outlet normally closed by a penetrable closure element, which device comprises a hollow body member 10 detachably secured to the container, a piston reciprocable in the body member, a discharge port in the body member between said piston and said outlet, a punch member operable by the piston to penetrate the closure element, the punch being tubular and having a lateral opening therein between the puncturing end thereof and said piston to convey fluid from said outlet to said port, one of said members being also formed with a by-pass providing constantly open communication between said port and the outer side of said piston to admit fluid under pressure to operate the piston, a check valve preventing inflow of fluid through said port to the cutting end of the punch, said check valve being located between the penetrable closure element and the point of communication of the by-pass with the discharge port, and manual means for operating the punch to penetrate the closure element.

2. A releasing device for a container holding fluid under pressure and having an outlet normally closed by a penetrable closure element, which device comprises a hollow body detachably secured to the container and formed with a cylinder chamber and with a discharge port 35 between said chamber and said outlet, a closure for the outer end of the chamber, a piston reciprocable in the chamber, a punch adapted to be operated by the piston to puncture said element, the punch being tubular and having a lateral opening 40 therein to convey fluid from said outlet to said port, the body being also formed with a passage providing open communication at all times from the port to said chamber at the outer side of the piston, a check valve in said 45 port preventing inflow from the port to the puncturing end of the punch, said check valve being located between the penetrable closure element and the point of communication of the by-pass with the discharge port, and manual 50 means for operating the piston to advance the punch.

3. A releasing device for a container holding fluid under pressure and having an outlet normally closed by a penetrable sealing element, which device comprises a hollow body detachably secured to the container and formed with a cylinder chamber and with a discharge port between said chamber and said outlet, a closure for the outer end of the chamber, a piston reciprocable in the chamber, a punch secured to the piston and adapted to be advanced thereby to puncture said sealing element, the punch being tubular and having a lateral opening therein to convey fluid from said outlet to said port, 60 the punch being also formed with a passage providing communication from said opening to the outer side of the piston, a check valve closing toward the puncturing end of the punch and located in the punch between said puncturing 65 end and said opening, and manual means for operating the punch.

4. A releasing device for a container holding fluid under pressure and having an outlet and a sealing disk closing the outlet, which device 70

75

comprises a body formed with a bore and constructed and arranged to be detachably secured to the container, a tubular cutter fitted in the bore and movable therein to penetrate the disk, 5 said bore having an enlargement at the outer end thereof to form a working chamber, a closure for the outer end of the working chamber, a piston fixed to the cutter and having a working fit in said chamber, the bore having another enlargement through which the cutter extends 10 forming a discharge chamber, a packing around the cutter separating said chambers, a discharge port leading from the discharge chamber, the cutter being formed with lateral ports opening 15 into the discharge chamber, a duct providing communication at all times between the discharge port and the working chamber at the outer side of the piston, a check valve preventing inflow of fluid from the discharge port to the 20 cutting end of the cutter, said check valve being located between the sealing disk and the point of communication of said duct with the discharge port, and manual means for advancing the cutter to penetrate the closure member.

25 5. A releasing device for a container holding fluid under pressure and having an outlet and a sealing disk closing the outlet, which device comprises a body formed with a bore constructed and arranged to be detachably secured to the 30 container, a tubular cutter fitted in the bore and movable therein to penetrate the disk, said bore having an enlargement at the outer end thereof to form a working chamber, a closure for the outer end of the chamber, a piston fixed to the 35 cutter and having a working fit in said chamber, the bore having another enlargement through which the cutter extends forming a discharge chamber, a packing around the cutter separating said chambers, a discharge port leading from 40 the discharge chamber, the cutter being formed with ports opening into the discharge chamber, the body being provided with a passage providing communication at all times between the discharge port and the outer end of the working 45 chamber, a check valve preventing inflow of fluid from the discharge port to the cutting end of the cutter, said check valve being located between the sealing disk and the point of communication of the passage with the discharge 50 port, and manual means for advancing the cutter to penetrate the closure member.

55 6. A releasing device for a container holding fluid under pressure and having an outlet and a sealing disk closing the outlet, which device comprises a body formed with a bore constructed and arranged to be detachably secured to the 60 container, a tubular cutter fitted in the bore and movable therein to penetrate said sealing disk, said bore having an enlargement at the outer end thereof to form a working chamber, a closure for the outer end of said chamber, a piston fixed to the cutter and having a working fit in said chamber, the bore having another enlargement through which the cutter extends 65 forming a discharge chamber, a packing around the cutter separating said chambers, a discharge port leading from the discharge chamber, the cutter being formed with ports opening laterally into the discharge chamber, the cutter being also 70 provided with a passage extending through the piston and providing communication between the outlet and the outer side of the piston, a check valve in the tubular cutter preventing inflow of fluid from said discharge port to the cutting end of the cutter, and manual means for 75

advancing the cutter to penetrate the sealing disk.

7. In combination, a container adapted to hold fluid under pressure, an outlet fitting secured thereto having a laterally disposed outlet, a sealing disk normally closing the outlet, a hollow discharge member detachably secured to the fitting over said outlet, said member having a discharge port and being formed with a cylinder chamber closed at its outer end, a piston 10 reciprocable in said chamber, a spindle threaded through said closed end and abutting the piston, means for turning the spindle to depress the piston, a punch member secured to the piston and movable thereby to penetrate the disk, the 15 punch being tubular and having lateral openings therein to convey fluid from said outlet to said discharge port, one of the members being also formed with a by-pass providing communication between said port and the outer side of 20 said piston, and a check valve preventing inflow of fluid through said port to the cutting end of the punch but permitting such inflow into said by-pass, said check valve being located between the sealing disk and the point of communication 25 of the by-pass with the discharge port.

8. A releasing device for use in connection with a fluid container having an opening and a closure for the opening, said device comprising a body forming a chamber, an operating member in said chamber, means whereby said operating member may be actuated, a puncturing member associated with said operating member, said puncturing member being operable by said operating member to puncture said closure, a 30 main discharge port in the body located between said closure and said chamber, means for conveying the released fluid to said port and a part of the fluid to said chamber so that the pressure thereof may be utilized to assist in the actuation of said operating member, means for relieving pressure opposing the actuation of said operating member, and a check valve for preventing said fluid from reaching said chamber until the pressure thereof exceeds the pressure 40 in said chamber.

9. A releasing device for use in connection with a fluid container having an opening and a closure for the opening, said device comprising a body forming a chamber, an operating member in the 50 form of a piston in said chamber, means whereby said operating member may be actuated, a puncturing member associated with said operating member, said puncturing member being operable by said operating member to puncture 55 said closure, a main discharge port, there being an opening in said puncturing member for receiving released fluid and passing it to said port and a passage in the body for leading part of the fluid to the chamber to assist in actuating 60 said operating member.

10. A device for opening a fluid container including, an opening member, fluid pressure actuated means for operating the opening member, a connection between the container and said means 65 allowing fluid released from the container to act on said means, and a pressure actuated control for said connection preventing fluid from the container from acting on said means until its pressure exceeds that actuating said means, 70 means for relieving pressure opposing the actuation of said fluid pressure actuated means, and a main discharge port for the released fluid located between the container and said means.

11. A releasing device for a container holding 75

fluid under pressure and having an outlet normally closed by a penetrable closure element, which device comprises a hollow body detachably secured to the container and formed with a piston chamber and a discharge chamber, the latter chamber having a discharge port, a piston reciprocable in the piston chamber, a punch passing through the piston and secured thereto and also passing through the discharge chamber and being operable by the piston to penetrate said closure member, said punch being tubular and being formed with an outlet to the piston chamber at the outer face of said piston and with an outlet to the discharge chamber, packing means surrounding the punch and preventing leakage of fluid from the discharge chamber into the piston chamber at the inner side of the piston, the punch being formed interiorly with opposed valve seats disposed respectively at opposite sides of the latter outlet, a valve within the punch, spring means normally holding the valve against the inner seat to prevent reverse flow of fluid from the discharge chamber to the cutting end of the punch but yieldable to fluid pressure from the container when the closure element is punctured, the outer valve seat being channeled to permit the fluid from the container to by-pass the valve when the latter is seated on said outer seat, and manual means for depressing the piston to puncture the closure member.

12. A releasing device for a container holding fluid under pressure and having an outlet normally closed by a penetrable closure element, which device comprises a hollow body member detachably secured to the container, a piston reciprocable in the body member, a discharge port in the body member between said piston and said outlet, a punch member operable by the piston to penetrate the closure element, the punch being tubular and having a lateral opening therein between the puncturing end thereof and said piston to convey fluid from said outlet to said port, one of said members being also formed with a by-pass providing constantly open communication between said port and the outer side of said piston to admit fluid under pressure to operate the piston, and a check valve preventing inflow of fluid through said port to the cutting end of the punch, said check valve being located between the end closure element and the point of communication of the by-pass with the discharge port.

13. A releasing device for a container holding fluid under pressure and having an outlet normally closed by a penetrable closure element, which device comprises a hollow body detachably secured to the container and formed with a cylinder chamber and with a discharge port between said chamber and said outlet, a closure for the outer end of the chamber, a piston reciprocable in the chamber, a punch adapted to be operated by the piston to puncture said element, the punch being tubular and having a lateral opening therein to convey fluid from said outlet to said port, the body being also formed with a passage providing open communication at all times from the port to said chamber at the outer side of the

piston, and a check valve in said port preventing inflow from the port to the puncturing end of the punch, said check valve being located between said element and the point of communication of the passage with the discharge port.

14. A releasing device for a container holding fluid under pressure and having an outlet normally closed by a penetrable sealing element, which device comprises a hollow body detachably secured to the container and formed with a cylinder chamber and with a discharge port between said chamber and said outlet, a closure for the outer end of the chamber, a piston reciprocable in the chamber, a punch secured to the piston and adapted to be advanced thereby to puncture the disk, the punch being tubular and having a lateral opening therein to convey fluid from said outlet to said port, the punch being also formed with a passage providing communication from said opening to the outer side of the piston, a check valve closing toward the puncturing end of the punch and located in the punch between said puncturing end and said opening.

15. A releasing head for a fluid container, provided with a pressure chamber at one end, pressure operated means in said chamber, a releasing element operated by said means and reciprocable through the other end of said head, said head being also provided with a discharge outlet and with a discharge chamber in communication with a bore in the free end of said element, with said discharge outlet and with said pressure chamber, and a valve between said discharge chamber and said bore in the releasing element seating in a direction to prevent flow of fluid from the former through the latter.

16. A releasing head for a fluid container, provided with a pressure chamber at one end, pressure operated means in said chamber, a releasing element operated by said means and reciprocable through the other end of said head, said head being also provided with a discharge outlet and with a discharge chamber in communication with a bore in the free end of said element, with said discharge outlet and with said pressure chamber through a bore in said head between said discharge outlet and said pressure chamber, and a valve between said discharge outlet and discharge chamber seating in a direction to prevent flow of fluid from the former to the latter.

17. A releasing head for a fluid container, provided with a pressure chamber at one end, pressure operated means in said chamber, a releasing element operated by said means and reciprocable through the other end of said head, said head being also provided with a discharge outlet and with a discharge chamber in communication with a bore in the free end of said element, with said discharge outlet and with said pressure chamber through a bore in said element, and a valve between said discharge chamber and first mentioned bore in said element seating in a direction to prevent flow of fluid from the former through the latter.

SCOTT E. ALLEN.
